EDWIN O. ROE, OF NEW BEDFORD, MASSACHUSETTS, ASSIGNOR TO NATIONAL SPUN SILK CO., INC., OF NEW BEDFORD, MASSACHUSETTS, A CORPORATION OF MASSACHUSETTS.

ROVING PEG OR BOBBIN HOLDER.

Application filed February 27, 1926. Serial No. 91,029.

This invention relates generally to improvements in textile machines and has particular reference to improvements in what are known as the roving pegs or bobbin holders used in such machines.

One object of the invention is to provide a device of the kind mentioned which will permit the bobbin to rotate very freely so that the thread or yarn will be subjected to a very slight pull or tension in unwinding it from the bobbin. Such a construction is very desirable for use in handling very light yarns or threads as to which strain or stress might cause an improper drawing or breakage. However, the improved construction embodies a feature which may be used to prevent overrunning of the bobbin and this feature may, by a very slight change or adjustment, be employed to create a greater tension on the yarn or thread if they are of such a nature or if the work to be done on them should require it.

Another object of the invention is to provide a bobbin holder so constructed that lint and the like cannot accumulate between the bobbin holder and the spindle in such a way as to increase the friction or tension on the yarn.

Another object of the invention is to provide a construction whereby the bobbin holder will not be detached when the bobbin is removed therefrom, thereby doing away with the trouble and loss now caused by failure of employees to see that holders pulled off by removing tight or warped bobbins are recovered and restored to position on the spindles.

With the foregoing and other objects in view, the invention consists in a novel combination and arrangement of parts the novel features of which are pointed out in appended claims, and a preferred embodiment of which is hereinafter described with reference to the drawings accompanying and forming a part of this specification.

In said drawings:

Fig. 1 is a side view, partly in section, of one of the improved bobbin holders.

Fig. 2 shows in section and on an enlarged

scale the construction of the upper end of the 50 bobbin holder and of the upper end of the spindle on which the holder rotates.

Fig. 3 shows a modified construction comprising a novel arrangement for creating and regulating frictional resistance to rotations 55 of the bobbin holder.

Figs. 4 and 5 are details of elements of construction employed in the modification shown in Fig. 3.

The construction shown in the drawing 60 comprises a spindle 10 secured in any suitable way, as by means of the nuts 11, to the frame 12 of the main machine. The spindle has preferably an enlarged portion 13 extending to a point near the outer or upper 65 end of the spindle, which end is reduced as at 14 and terminates in a point 15. This point is shown as being substantially conical in shape.

Surrounding the spindle 10 is a cylindrical 70 bobbin holder 16, the main part 17 of the interior of which is tubular and of a greater diameter than the spindle. The head or end 18 of the spindle is rounded or otherwise shaped to serve as a guide in putting 75 a bobbin 19, carrying the yarn or thread 20, on the holder.

The interior of this end 18 of the holder is provided with a cylindrical recess 21 to receive the reduced end 14 of the spindle in 80 such a way as to surround the reduced end and with the point 15 in contact with the closed end of the recess. This construction provides a satisfactory pivot support and bearing for the upper end of the spindle and 85 leaves a small compartment 22 around the pointed end of the spindle for a lubricant.

The lower end of the holder 16 is threaded 90 preferably on the exterior, to cooperate with corresponding threads on a cap or skirt member 23. The member surrounds the lower reduced portion of the spindle 10 so that when it is in normal position it forms a lower bearing for the holder. The inner wall 24 of 95 the member 23 is adjacent the lower shoulder of the enlargement 13 on the spindle. When a very free running holder is desired the inner wall 24 may not be normally in frictional

engagement with the shoulder on the spindle, but where over-running is to be prevented the member 23 may be made adjustable so that a slight friction is created between the 5 wall 24 and the shoulder.

Instead of making the member 23 adjustable the construction shown in Figs. 3, 4 and 5 may be employed. In this construction an open sided washer or weight 26 10 rounds the enlarged portion 13 of the spindle 10 and rests upon the inner surface 24 of the skirt 23. The interior of the element 26 is provided with a lug or rib 27 engaging a longitudinal slot 28 in the stationary spindle 10. It is apparent that this construction provides a satisfactory way of creating frictional resistance to rotations of the holder 16 and that by using elements 26 of different mass or by using different members of such 20 elements the frictional resistance may be regulated according to the effect desired.

It is obvious that when the member 23 is in normal position, the position in which it is shown in the drawing in both of the constructions described, the inner wall of the member and the shoulder on the spindle will cooperate to prevent the withdrawal of the holder 16 from the spindle when removing an empty bobbin.

30 The exterior of the cap or skirt 23 is beveled as shown at 25, thereby serving to center the bobbins on the holder.

When it is desired to remove the bobbin holder for any purpose, as, for example, to renew the lubricant, the member 23 is unscrewed, thereby allowing the body of the holder to be removed. After lubricating the parts are restored to normal position and relation, thereby closing the bobbin holder so 40 that the bearings are fully protected from dust and lint.

From the foregoing it will be seen that the construction shown and described is admirably adapted to fulfill the purposes primarily stated and that certain modifications may be made to adapt the idea to specific conditions without departing from the spirit 45 of the invention, such modifications all coming within the scope of the claims which 50 follow.

What is claimed is:—

1. In a device of the character described, 55 the combination of a stationary spindle, a tubular bobbin holder closed at one end and having the interior of said end constructed to form a bearing cooperating with the outer end of the spindle, a screw cap surrounding the spindle and closing the other end of the holder and forming a second bearing for the 60 holder, and means on the spindle cooperating with the cap to prevent withdrawal of the holder from the spindle until the cap is unscrewed.

2. In a device of the character described,

the combination of a stationary spindle, a 65 bobbin holder closed at its outer end and having the interior of said end constructed to form a bearing cooperating with the outer end of the spindle, a skirt member surrounding the spindle and closing the other end of 70 the holder, said skirt member having threads cooperating with the threads on the holder, and constituting a second bearing for the holder, and an enlarged portion on the spindle cooperating with the skirt member to 75 limit the holder to rotary movement when the member and holder are screwed together.

3. In a device of the character described, 80 the combination with a spindle having a reduced cylindrical portion at its upper end terminating in a point and a second reduced portion near the lower end of the spindle, of a rotary bobbin holder surrounding the spindle and having its upper interior constructed to provide a cylindrical recess to rest upon the point and surround the sides of the aforesaid reduced point bearing portion of the spindle to form a pivot bearing, a screw cap closing the other end of the bobbin holder and cooperating with the lower reduced portion of the spindle to form a second bearing for the holder, said cap cooperating with the shoulder above the reduced portion on the spindle to prevent endwise movement of the holder when the cap is in place. 95

4. In a device of the character described, 100 the combination with a spindle having a reduced portion at its upper end terminating in a point and a second reduced portion near the lower end of the spindle, of a bobbin holder surrounding the spindle and having its upper interior constructed to provide a cylindrical recess to receive the aforesaid point bearing reduced end of the spindle, a screw cap closing the other end of the bobbin holder and cooperating with the lower reduced portion of the spindle to form a second bearing for the holder and cooperating with the shoulder on the spindle to prevent withdrawal of the holder until the screw cap is removed. 110

5. In a device of the character described, 115 the combination with a spindle having a reduced portion at its upper end terminating in a point and a second reduced portion near the lower end thereof, of a bobbin holder surrounding the spindle and having its upper interior constructed to surround the aforesaid pointed end of the spindle, said holder being provided with threads at its lower end, a skirt surrounding the second reduced portion of the spindle shaped to effect centering of the bobbins on the holder and provided with threads engaging the threads on the bobbin holder. 120

6. In a device of the character described, 125 the combination with a stationary spindle, of a bobbin holder rotatably mounted on

the spindle and having an interior bearing near each end engaging the spindle, a projection on the spindle cooperating with the interior of the holder adjacent the lower bearing to prevent withdrawal of the holder when a bobbin is being removed therefrom, and means whereby said projection and the

holder may be caused to cooperate to create varying degrees of frictional resistance to rotations of the holder.

10

In testimony whereof I hereto affix my signature.
